CAST DECORATIVE PANEL FOR METAL FURNITURE

Lester Grundy, New York, N. Y., assignor to Molla Incorporated, Westbury, N. Y., a corporation of New York

Application January 26, 1956, Serial No. 39,927

Term of patent 14 years

(Cl. D54—2)

The figure is a front elevation view of a cast decorative panel for metal furniture showing my new design, the rear being the same.

The nature of the device is thin and substantially of one thickness, as viewed edgewise.

The characteristic features of my design for the decorative panel disclosed reside in the coral pattern having the configuration shown.

I claim:

The ornamental design for a cast decorative panel for metal furniture, as shown and described.
